UNITED STATES PATENT OFFICE

WALTER A. BISHMAN AND HAROLD G. LIEN, OF MINNEAPOLIS, MINNESOTA

WRENCH FOR AUTOMOBILE HUB CAPS

Application filed March 20, 1929. Serial No. 348,579.

This invention relates to wrenches and especially to wrenches for removing the hub caps of automobiles although, of course, capable of other use.

At the present time a wide variety of distinctive hub caps are employed on the many different automobiles commercially sold. These hub caps are provided with various different engagement means by which they may be removed from the wheel. Many of the newer models of automobiles, employ hub caps having flanges of relatively wide diameter and provided with nuts disposed inwardly of said flanges.

It is an object of our invention to provide a simple, compact wrench which will have practically universal application to hub caps on motor vehicles sold at this time, and which is adjustable where an external contracting wrench is required and also where an internal expanding wrench is required.

A further object of our invention is to provide a universal hub cap wrench which will afford adequate leverage for removing hub caps, which may be quickly and easily applied and adjusted and which makes provision for the wide flanges of many of the hub caps now in use without requiring a mechanic to work within close and objectionable proximity to the wheel.

It is a more specific object to provide a wrench having a pair of rectilinearly adjustable jaw heads each head carrying several cooperating elements, and simple means for positively varying the relative position of said jaw heads in either direction whereby some of the cooperating members of the two jaws may be used for external contracting purposes and others used for internal expansion purposes.

These and other objects and advantages of the invention will be apparent from the following description made in connection with the accompanying drawing, wherein like reference characters refer to similar parts

throughout the several views and in which,

Fig. 1 is a plan view of an embodiment of our invention showing two of the cooperating members applied to an octagonal nut of a flanged hub cap;

Fig. 2 is a front elevation of the same;

Fig. 3 is an end elevation of the same at the end on which the adjusting sleeve is mounted;

Fig. 4 is a longitudinal section taken on the line 4-4 of Fig. 1;

Fig. 5 is a cross section taken on the line 5-5 of Fig. 1 showing the application of two of the cooperating jaw elements with an octagonal nut;

Fig. 6 is a similar view showing the application of two of the other cooperating jaw members with a hexagonal nut;

Fig. 7 is a plan view with some portions broken away, showing the application of two of the external expanding cooperating jaw elements;

Fig. 8 is a section taken on the line 8-8 of Fig. 7;

Fig. 9 is a view similar to Fig. 7 showing the application of two other cooperating jaw members; and

Fig. 10 is a cross section taken on the line 10-10 of Fig. 9.

The embodiment of the invention illustrated in the drawing comprises a pair of cooperating jaw heads, one a relatively fixed member, indicated as an entirety by the letter A and the other a relatively movable member indicated as an entirety by the letter B. Jaw head A has a straight handle portion 11, of preferably polygonal cross section and a forked inner portion comprising two widely spaced contracting jaw elements 12 and 13 respectively. These elements extend outwardly from handle member 11 and then are turned substantially parallel with the axis of handle 11. Member 12 terminates in an external V-shaped clamping edge 12a angulated at 45° to exactly fit octagonal nuts of different sizes.

Element 13 is extended in symmetrical manner with element 12 but terminates in an angular clamping edge 13a angulated at 60° to engage hexagonal nuts. Head B has inwardly 5 extended spaced jaw elements 12 and 13 formed similar to elements 12 and 13 respectively of head A and provided with angular clamping edges 12a and 13a adapted to cooperate with the edges 12a and 13a respectively of jaw 10 head A and disposed diametrically opposite therefrom. Head A carries a central inward projection 14 axially aligned with handle 11 and this projection carries on opposite faces thereof an expanding clamping element 15 15 and an engagement pin 16. As shown, the engagement pin is in the form of a set screw having threaded connection with the projection 14 and projecting a sufficient distance from said projecting portion to engage a 20 socket or recess. The elements 15 and 16 project radially from the axis of handle member 11 at an angle of 90° from elements 12 and 13. Head B carries an inwardly extending projection 14 similar to the projection 14 of head 25 A and said projection is provided with laterally projecting clamping and engagement elements 15 and 16 being oppositely disposed to the cooperating elements 15 and 16 of head A. It will be noticed that the elements 15 have 30 outer angular engagement surfaces 15a adapted to precisely engage an internal hexagonal nut, as best shown in Figs. 7 and 8, but capable of efficiently engaging octagonal or other internal nuts.

35 Handle portion 11 of head A has a longitudinal passage of substantially oblong cross section extending therethrough, in which a bar or shank 17 is non-rotatably disposed. Bar 17 is rigidly secured to jaw head A by any 40 suitable means, such as by means of the set screw element 16, which acts as one of the cooperating engagement elements of the wrench. Bar 17 projects a considerable distance beyond the inwardly projecting portion 45 14 of head A and has a heavy external thread 17a at its outer portion. Head B is provided with a bore of substantially oblong cross section to non-rotatably accommodate the projecting portion of bar 17. Bar 17 is free to 50 slide through head B.

An adjusting sleeve 18 of substantially the size and shape of handle element 11 is connected to the outer end of head B and has a large inner bore 18a provided with several 55 internal heavy threads 18b adjacent the inner end thereof, said threads engaging the threads 17a of the bar 17. The inner end of adjusting sleeve 18 is provided with a circumferential groove 18c, the grooved portion being 60 swivelly connected with inturned retaining ears 19 at the outer end of head B. Said ears are of such strength that head B may be positively moved away from head A, but when head B is moved in the opposite direction the 65 inner extremity of adjusting sleeve 18 abuts

against a smooth surface at the outer end of head B.

It will be noticed that in both of the heads A and B the cooperating jaws 12 and 13 are spaced a considerable distance from the inward projection portions 14 of said heads leaving recesses 20 to accommodate the wide ornamental flanges or other outwardly projecting portions carried by many of the hub caps in use at this time (see Figs. 1 to 3). 75

Operation

In the drawing, the application of our device on several different standard types of hub caps is illustrated. In Figs. 1 to 3 the 80 wrench is shown applied to an external nut of a hub cap having a relatively wide outer flange. Such hub caps at the present time are employed on several different automobiles such as the Chrysler and the Studebaker. 85 The flanged portion of the hub cap as clearly shown in Fig. 1, is accommodated by the oppositely disposed recesses 20 in the heads A and B. The cooperating jaw elements 12 precisely engage the octagonal nut disposed inwardly of the hub cap. The jaws are clamped or adjusted by holding the handle 11 of head A in one hand and turning the adjusting sleeve 18 in clockwise direction with the other hand, head B sliding upon the shank or bar 17 which passes therethrough. The hub cap is then turned by swinging the wrench grasped by handle 11 and adjusting sleeve 18. 90

It will be seen that adequate leverage is provided for removing large nuts which are 100 tightly secured. In Fig. 1 it will be seen, that even though the nut of the hub cap is disposed inwardly of the flange and in close proximity to the spokes and other parts of the wheel, a mechanic may easily and quickly remove the 105 hub cap and the handles of the instrument will be spaced a sufficient distance from the wheel, to permit easy manipulation of the wrench.

Hexagonal nuts may be removed by employing the hexagonal cooperating jaw elements 13 of the wrench in the manner illustrated in Fig. 6. 110

Several standard makes of automobiles, such as the Packard employ internal nuts at 115 the outer extremity or flange of the hub cap. Here the device is employed, as illustrated in Figs. 7 and 8, the cooperating expanding elements 15 being expanded by manipulating adjusting sleeve 18 to properly engage an 120 internal nut. The wrench is then swung to unscrew the hub cap from the wheel.

In Figs. 9 and 10, the application of the wrench on still a different form of hub cap is shown. Some cars, such as the Whippet have 125 a pair of spaced sockets or a slot in the outer face of the hub cap and in such case the cooperating engagement pins 16 may be adjusted to properly fit the sockets or slot and the wrench then swung to remove the hub cap. 130

From the foregoing description it will be seen that we have provided a highly efficient wrench comprising only four different parts which may be manufactured at low cost and which while especially adapted for removing and tightening most types of hub caps commercially used at this time, is capable of wide general use for removing and tightening internal or external nuts on various different devices.

It will be noticed that the jaw heads are positively separated and moved together by the manipulation of the so-called adjusting sleeve 18, the cooperation of the heads, bars 17 and adjusting sleeve and the several cooperating jaw elements permits the wrench to be used for various contracting purposes and also expansion purposes.

It will, of course, be understood that various changes may be made in the form, details, arrangement and proportions of the parts without departing from the scope of applicant's invention.

What is claimed is:

1. A wrench comprising a pair of cooperating jaw heads, means for connecting said heads for movement together and apart, said heads rigidly carrying cooperating L-shaped jaw elements projecting laterally therefrom, the turned ends of said L-shaped elements extending inwardly and terminating in opposed angularly shaped gripping edges, said elements defining a large recess disposed inwardly of said extremities and between the inner ends of said jaw heads whereby an outwardly projecting enlargement of an object to be turned may be accommodated.

2. In a hub cap wrench, a pair of cooperating jaw-carrying heads, a bar extending longitudinally of said heads and connected therewith to permit relative movement between said heads, said heads rigidly carrying cooperating L-shaped jaw elements projecting laterally therefrom, the turned ends of said L-shaped elements extending inwardly for some distance and being off-set considerably from said bar and terminating in opposed V-shaped gripping surfaces for clamping the inwardly disposed nut of a hub cap, said elements defining a large recess disposed inwardly of said extremities and between said extremities and said bar whereby the enlarged outer flange of the hub cap may be accommodated.

3. A wrench comprising a pair of cooperating jaw-carrying heads, one of said heads having a handle rigidly connected with the outer end thereof, a bar rigidly connected with the inner end of said head and projecting therefrom axially of said handle portion, the other of said jaw-carrying heads being mounted for slideable movement on said bar and a movable handle member swivelly connected to the outer end of said second jaw carrying head and threadedly engaging the out-

er portion of said bar, said heads having cooperating L-shaped arms extending laterally therefrom, off-set considerably from said bar, and said heads also having opposed inwardly extending projections at their inner ends aligned with said bar and terminating at points disposed inwardly of said L-shaped arms.

In testimony whereof we affix our signatures.

WALTER A. BISHMAN.
